UNITED STATES PATENT OFFICE.

HENRY W. STAUFFER, OF READING, AND AUSTIN H. RIEGNER, OF MOHN'S STORE, PENNSYLVANIA.

SPLIT COLLAR.

SPECIFICATION forming part of Letters Patent No. 727,707, dated May 12, 1903.

Application filed July 22, 1902. Serial No. 116,502. (No model.)

To all whom it may concern:

Be it known that we, HENRY W. STAUFFER, residing in the city of Reading, and AUSTIN H. RIEGNER, residing at Mohn's Store, in the 5 county of Berks, State of Pennsylvania, citizens of the United States, have invented certain new and useful Improvements in Split Collars, of which the following is a specification.

10 Our invention relates particularly to split collars for shafting; and our main object is to provide a simple construction consisting of similar sections adapted to be conveniently interlocked upon the shaft in such manner 15 as to insure their being held rigidly in line thereon.

The invention is fully described in connection with the accompanying drawings, and the 20 novel features are specifically pointed out in the claim.

Figure 1 is a sectional elevation of the similar united sections. Fig. 2 is a perspective view showing the two sections separated in position to be closed together upon the shaft- 25 ing.

The two half-ring sections shown are alike in form, being simply reversed in position upon the shaft, with each section encircling one-half thereof and abutting against the 30 other at *a a* upon the diametral line *d d*.

To provide for interlocking and securing the sections together upon the shafting, we form the abutting portions of each with differently-shaped overlapping extensions, where- 35 by the two sections are adapted to engage each other, as shown. One of these exten- sions *b* forms a continuation of the peripheral portion of the collar and overhangs the abutting portion of the reversely-set opposing sec- 40 tion, while the other extension *c* of each sec- tion is adapted to interlock interiorly with the opposing section by extending beyond the diametral line *d d* into a receiving-recess *e* therefor, formed between the abutting ends 45 of the flanges *f f*, the curved inner faces of which latter encircle the shafting. The two sections of the collar when thus engaged are

firmly held sidewise, so as to prevent their getting out of line, and they are rigidly secured together and to the shafting by means 50 of opposite set-screws *g g*, passing radially through the respective overlapping exten- sions *b c* in the abutting plane *d d* and force- 55 bly seated against the surface of the shafting. To prevent any projection of the heads of these screws above the surface of the collar, a peripheral recess *h* is provided therefor in each section.

In the construction shown the flanges *f f* form between their laterally-spaced ends 60 within the overlapping extension *b* the eng- aging recess *e* for the underlapping extension *c* of the opposing section, the flattened exte- 65 rior portion *k* of which latter is covered by said extension *b*.

The sections of our improved collar, it will be seen, are simply and cheaply formed, may be secured to the most limited space upon the shafting, no endwise movement being re- 70 quired, and are secured together in positive alinement and to the shafting in a simple and effective manner.

What we claim is—

A shaft-collar made up of two similar half- 75 ring sections abutting on a diametral line, the abutting portions of each section being provided with an overlapping extension *b* and laterally-spaced flanges *f* on one side of the shaft, and with an underlapping extension *c* on the opposite side thereof, said underlap- 80 ping extension of each section being engaged between the spaced flanges of the reversely- set opposing section; and radial uniting- screws entering alined openings in each pair of lapping extensions substantially as set forth.

In testimony whereof we affix our signatures in the presence of two witnesses.

HENRY W. STAUFFER.
AUSTIN H. RIEGNER.
